UNITED STATES PATENT OFFICE.

ABRAHAM B. LANDIS, OF WAYNESBOROUGH, PENNSYLVANIA.

CARRIAGE-OPERATING MECHANISM FOR GRINDING-MACHINES.

SPECIFICATION forming part of Letters Patent No. 639,900, dated December 26, 1899.

Application filed August 26, 1899. Serial No. 728,584. (No model.)

To all whom it may concern:

Be it known that I, ABRAHAM B. LANDIS, a citizen of the United States, residing at Waynesborough, in the county of Franklin 5 and State of Pennsylvania, have invented certain new and useful Improvements in Carriage-Operating Mechanism for Grinding-Machines, of which the following is a specification.

10 My said invention relates to various improvements in the construction and arrangement of parts of grinding-machines of that character shown in Patents Nos. 483,288, 544,439, and others heretofore granted to me; 15 and it consists particularly in certain improvements in the mechanism for automatically reversing the travel of the emery-wheel carriage, whereby the point of reversing may be set to a very fine point and adjusted as desired to suit any job of work, all as will be hereinafter more fully described and claimed.

Referring to the accompanying drawings, which are made a part hereof and on which similar reference characters indicate similar 25 parts, Figure 1 is a side elevation of a grinding-machine embodying my said improvements; Fig. 2, a transverse section through the machine on the dotted line 2 2 in Fig. 1; Fig. 3, a detail view, partly in section, of a portion of Fig. 1 on an enlarged scale as seen when looking in the direction indicated by the arrows from the dotted line 3 3 in Fig. 4; Fig. 4, a transverse section on the dotted line 4 4 in Fig. 3; Fig. 5, a detail view of the dogs and 35 upper portion of the wheel carrying the same, which operate or trip the reversing mechanism; Fig. 6, a cross-section on the dotted line 6 6 in Fig. 5, and Fig. 7 a detail section on the dotted line 7 7 in Fig. 2.

40 In said drawings the portions marked A represent the frame of the machine, B the emery-wheel carriage, C the emery-wheel base, D the head-stock, and E the foot-stock, all of which parts are or may be of any approved 45 construction, as they form no part of this invention, except in a general way they must be of a form adapted to be used and operate therewith.

The machine is driven by a main shaft 1 50 from any convenient source of power connected by belts with the pulleys 2 thereon. Said shaft is journaled in bearings 3, 4, and 5,

mounted on the frame, and on its inner end is formed with a pinion 6, which meshes with a gear-wheel 7, mounted on a counter-shaft 55 8, journaled in suitable bearings above said shaft 1. A beveled pinion 9 is mounted on the inner end of said shaft 8 and meshes with a bevel-gear 10 on the carriage-driving shaft 11, whereby said carriage is driven. Said 60 wheel 7 has one part 13 of a clutch on its hub. The double-faced part 14 of the clutch is secured by a spline on said shaft, and another wheel 15, corresponding to wheel 7, with a similar clutch part on inner hub, is also mounted 65 on said shaft 8. Said double-faced part 14 of the clutch is adapted to be shifted by a shifting-fork 16, mounted rigidly on a rock-shaft 17, which is journaled in suitable bearings in the frame. The prongs of said fork are provided with antifriction-rollers 18 on their adjacent faces near their outer ends, which engage in a circumferential groove in said part 14, as is usual. The pinion 6 on shaft 1 is of considerable length, as shown, and meshes 70 with a pinion 19 on a counter-shaft 20, which is mounted in suitable bearings alongside said shaft 1 and just behind it. Adjacent to the gear-wheel 15 said shaft 20 is provided with a pinion 21, which meshes therewith. By this 75 arrangement, as will be readily understood, when wheel 7 is locked to shaft 8 through the clutch mechanism said shaft will be driven in one direction from shaft 1 direct, but when wheel 15 is locked to shaft 8 by the shifting 80 of clutch part 14 the said shaft 8 will be driven in the opposite direction through pinion 21, shaft 20, and its connection to shaft 1, just described. Said clutch part 14 may be shifted 85 and the travel of the carriage B changed by 90 hand through the medium of the lever 22 on the shaft 17 or by the automatic shifting mechanism hereinafter described.

The carriage-driving shaft 11 is journaled in suitable bearings and has a pinion 23 on 95 its inner end, which meshes with a longitudinally-extending toothed rack-bar 24 on the underside of carriage B. Said carriage is mounted in suitable ways to travel back and forth on the frame, as is well understood. The bevel-gear 10 is mounted loosely on said shaft 11, the outer end of its hub abutting against a rigidly-fixed collar 25, and a tapered face 100 is formed on a hub portion on the inside of

the wheel to serve as a part of a friction-clutch. The other part 26 of said clutch consists of a heavy ring or collar having a correspondingly-tapered inner face adapted to fit over and engage the tapered face of said hub. Its opposite end has a transverse groove and a key 27, which extends through an elongated mortise in said shaft 11, engages with said groove and locks said part 26 to said shaft.

10 A central longitudinal perforation extends from the outer end of said shaft to the slot containing the key 27, and a rod 28 is mounted therein with its inner end abutting the edge of said key. The outer end of said perforation is screw-threaded, and a screw 29, with a hand-wheel or thumb-nut on its outer end, is mounted therein, with its inner end bearing against the outer end of said rod. It will thus be seen that by turning said screw to 15 force said rod inward it will in turn force the key 27 and clutch part 26 inward, thereby bringing the two friction-surfaces of the two clutch parts together and locking the gear 10 to shaft 11 and starting said shaft in motion.

20 By backing said screw 29 sufficiently to permit, the weight of the work will quickly release the engagement and said shaft will stop.

Alongside the part 26 is a pinion 30, mounted on shaft 11 and connected thereto by a 25 transverse groove in its hub or flange, which also engages the key 27, the flange of part 26 being bored out to permit that of said pinion to pass within, as shown, or of course the parts 26 and 30 could be formed in one piece,

30 the object in forming as described being to permit the pinion to be of steel and the other part of cast metal, and thus secure the greatest efficiency at the smallest cost of construction. Said pinion 30 meshes with gear 31,

35 which is keyed to shaft 32, which is journaled in suitable bearings, and has a pinion 33 formed on its opposite end, which meshes with a gear 34, formed around a circumferential flange *f* on the wheel 35, which carries the dogs 36. Said wheel 35 has an elongated central hub *h*, which is mounted on shaft 11, which shaft is journaled in a suitable bearing 37 in the frame. Said shaft and the parts thereon are held in place by the collar 25 and wheel 40 on one side and the hand-wheel 38, rigidly secured on the outer end of said shaft. Mounted on the flange *f* of the wheel 35 is a ring 39, having an upwardly-extending arm 40 and a downwardly-extending arm 41, forming a lever. Said arm 40 has a strike 42, mounted on a transversely-extending pin 43, between ways or flanges on the top thereof, said pin extending through a vertical slot in one of said flanges and serving as a means for 45 lifting said strike out of the way of the dogs, when desired, as will be presently described. The downwardly-extending arm 41 is connected at its lower end by means of a link 44 to the lower end of a downwardly-extending arm 45 on the rock-shaft 17, carrying the shifting-fork 16. Said wheel 35 is formed with a concave periphery in cross-section having a worm-gear thereon. It is also formed with a circumferential groove *g* in its face near its periphery. On said periphery, held in said 70 grooves, are mounted the dogs 36. Said dogs consist of blocks of suitable dimensions, the upper corners of the adjacent faces of which are adapted to contact with the strike 42 and turn the ring 39 on its pivot sufficiently to shift 75 the clutch 14 through the arm 41, link 44, and connecting parts, above described. Each of said blocks rests upon the outside smooth corners of the wheel 35 and has flanges which extend down on each side thereof. On the front side a curved rib or segment 46 is secured on the inner face of the flange and engages the groove *g*, and thus secures said block to said wheel. Its outer end is bored out, as shown, to receive the shank of a short worm-gear 47. 80 The inner end of said shank is bulb-shaped and the seat therefor correspondingly formed in order to allow both rotatory and vertical motion of the worm. It is secured in said seat by means of a spring 48, which has a 85 head on its outer end and extends through a central perforation in said worm and shank. A head on its outer end seats in a countersunk outer portion of said perforation, and its inner end is secured by a transverse screw 49, which 90 extends through and clamps said spring. There is sufficient space left in the upper part of the seat (see Fig. 5) for its shank to permit said worm to be lifted sufficiently to 95 disengage it from the gear in the periphery 100 of the wheel, and a concave depression in its outer end furnishes a convenient hold for the thumb, the fingers being placed against the face of the dog to seize and raise said worm. Upon being released the spring 48 immediately returns and retains said worm into engagement with the gear on the wheel. By 105 this means the dogs can be adjusted to any position desired on the wheel, so that the travel of the carriage can be regulated to suit 110 the length of the work being ground. By taking hold of the dog, as above explained, and lifting the worm out of engagement with the gear it can be readily slid around the periphery to any position desired, and by turning 115 the worm after its engagement its position can be very finely adjusted, so that the finest and most accurate work can be done. The periphery of the worm may be roughened or knurled, if desired, as shown at the right in 120 Fig. 5, to afford a better hold for the thumb and finger in turning during the operation of adjusting. When for any reason it is desired that the grinding shall continue beyond the fixed point, the operator can raise the 125 strike 42 out of the path of the dogs, when the carriage will continue to the point desired, when the shifting mechanism can be thrown by the hand-lever 22. This can be done without disturbing the adjustment of 130 the dogs to the slightest degree, and the desired result being accomplished, as the removing of some imperfection, the automatic operation will continue as before between

the exact points for which the machine is set. In adjusting the parts before the operation begins the hand-wheel 38 is used to bring the carriage to the desired point, as will be 5 readily understood.

Below the lower end of the arm 41 is mounted a block 50, the top of which is tapered or concaved on each side of the center, forming a double cam-face. Said block is mounted 10 in a suitable socket on the frame upon a stiff spring, which tends to force the same upward. Its apex is in the path of an antifriction-roller 51 on the lower end of arm 41, and as said arm is thrown back and forth in operation it passes over said block, depressing the same until it passes over its apex, when the force of the spring operates to quickly throw said arm to one side, and thus throw the clutch part 14 after it has been released 15 from one gear-wheel by the first movement of the arm through the contact of the appropriate dog quickly into engagement with the other. As will be noticed by reference to Fig. 3, considerable play is left between the 20 antifriction-rollers on the ends of the shifting-fork prongs and the sides of the groove in part 14, which allows the roller on the lower end of extension 41 to pass well over the apex of the cam-block before the clutch 25 is disengaged, when the spring will effectually throw said clutch 14 into engagement with one of the other clutch parts, which action makes the shifting quick and at the exact point desired.

35 The operation of the several portions of the mechanism having been described above, the operation of the whole may be briefly recapitulated, as follows: The carriage may be moved by hand through the hand-wheel 38 to bring the work into the exact relation desired with the emery-wheel, so that the dogs can be set at the exact point to continue the grinding over that portion of the article desired to be ground and no further, the dogs 40 being moved to position and then finely adjusted by turning the worms, as before described. The machine is started in operation by connecting the shaft 1 with the power and throwing clutch part 14 to engage the wheel 45 on shaft 8, which will drive said shaft in the desired direction. The clutch 26 is then forced into engagement with wheel 10, which starts shaft 11 and the carriage B and the other mechanism operated by said shaft. When 50 the carriage has traveled to bring the work to the point where the grinding is to stop, the appropriate dog 36 will contact with the strike 42 and through the mechanism described 55 shift the clutch part 14 and start the carriage 60 back. When the point at which the grinding should stop at the other end is reached, the same operation is repeated. Thus the carriage will continue to travel back and forth without attention until the operation is completed, and the length of its travel can be 65 made as long or as short as desired and adjusted to a thousandth of an inch, so that the

finest and most delicate work can be accurately done.

Having thus fully described my said invention, what I claim as new, and desire to secure by Letters Patent, is—

1. In a carriage-shifting gear, the combination, of the gearing for driving said carriage in either direction, the shifting mechanism 70 for changing from one direction to the other, and mechanism for operating said shifting mechanism consisting of a pivoted arm or lever connected at one point to said shifting mechanism and having a strike or contact-point thereon mounted to be driven by the carriage-driving mechanism across the path of said strike, said dogs being mounted to be adjusted on the part which carries them, whereby said lever may be thrown, and 75 through it the shifting mechanism at different points, substantially as set forth.

2. In a carriage-shifting mechanism, the combination of the carriage-driving gear, the gear for shifting its direction, and mechanism 90 for operating the same consisting of dogs mounted on a part driven from the carriage-driving gear, and adapted to strike and throw the shifting mechanism, said dogs being mounted to be adjusted to different relative 95 positions on the part which carries them by means of a worm-gear, substantially as set forth.

3. In a carriage-shifting mechanism, the combination, of the carriage-driving gear, the 100 gear for shifting its direction and mechanism for operating the same, which consists of a lever pivoted around the carriage-operating shaft connected at one end to the shifting device, and at the other end carrying a strike, 105 a wheel mounted to be operated by said shaft and carrying adjustable dogs arranged to come in contact with said strike and operate said lever, and through its said shifting device, and said dogs, substantially as set forth. 110

4. In a shifting mechanism, the combination, of the operating-gear, the shifting device, an operating-lever connected therewith, and a wheel carrying dogs arranged to contact with said lever and operate it to operate 115 said shifting device, and said dogs, consisting in part of worm-gears which engage with a worm formed on the periphery of said wheel, whereby they may be finely adjusted and exactly held in place, substantially as set forth. 120

5. In a shifting mechanism, the combination, of the operating-gear, the shifting device, an operating-lever connected therewith, and a wheel carrying dogs arranged to contact with said lever to operate it and through 125 it the shifting device, said wheel being formed with a worm on its periphery and an annular groove in its side, and said dogs consisting of blocks which have a part engaging said groove to slide therein, and worm-gears which engage with said worm on the periphery of the wheel, substantially as set forth.

6. In a shifting mechanism, the combination, of the operating-gear, the shifting de-

vice, the lever for operating said shifting device, a strike thereon mounted to be adjusted within or without the path of the dogs, the wheel carrying the dogs, and the dogs mounted on said wheel, substantially as set forth.

7. A device for operating the shifting mechanism of a carriage-operating gear consisting of a lever, and a wheel carrying dogs adjustable thereon by worm-gear, which dogs are arranged to strike and operate said lever, substantially as set forth.

8. In a carriage-operating mechanism, the combination, of the carriage-operating shaft, a gear-wheel loosely mounted thereon, a clutch mechanism for locking it to said shaft, a shaft geared to said wheel, two gear-wheels loosely mounted thereon each carrying a clutch part, a double-faced clutch part mounted between them for locking one or the other to said shaft, shifting mechanism for throwing said clutch part into engagement with one or the other, the main driving-shaft geared directly to one of said wheels and through a countershaft to the other, the mechanism operated by said carriage-operating shaft for automatically operating said shifting mechanism to reverse said carriage at the point desired, substantially as set forth.

9. The combination, in a carriage-operating mechanism, of the main shaft, the countershaft geared to the carriage-operating shaft, gear connecting said main shaft and said counter-shaft for driving it in both directions, shifting mechanism, for throwing either gear into operation, said carriage-operating shaft, a ring pivoted around its outer end with an arm extending out from opposite sides thereof, forming a lever, a connection from one of said arms to the shifting mechanism, a strike on the other arm, a wheel journaled in bearings around the outer end of said carriage-shaft, dogs mounted on said wheel in position to contact with said strike, said wheel carrying the dogs being geared to said carriage-shaft, substantially as set forth.

10. In a carriage-operating mechanism, the combination, of the shaft geared to said carriage, the driving mechanism therefor, the shifting mechanism, the dog-carrying wheel mounted around the outer end of said shaft and provided with a toothed flange on its inside face, a pinion meshing therewith and driven through suitable gear from said shaft, the dogs mounted on said wheel, the lever pivoted around said wheel with which said dogs are adapted to contact, and connections from said lever to the shifting mechanism, substantially as set forth.

11. In a carriage-operating mechanism, the combination, of the carriage-operating shaft,

the driving-gear therefor, the clutch for connecting said gear with said shaft, said clutch being connected to said shaft by a key mounted in a longitudinal perforation in said shaft and bearing against said key, a screw in the outer end of said perforation for adjusting the rod, and the shifting mechanism, also operated from said carriage-shaft, substantially as set forth.

12. In a carriage-shifting mechanism, the combination, of the driving-gear, shifting device, the mechanism for operating said shifting device consisting of a lever connected thereto, a wheel carrying dogs arranged to strike a point on said lever and operate it, gearing connecting said wheel to the driving mechanism, said dogs being mounted on said wheel to slide and adjustably held by means of a worm-gear, said gear being connected to the base of the dog by a spring, whereby it may be lifted out of engagement when desired, substantially as set forth.

13. In a carriage-operating mechanism, the driving-gear, the shifting device, the mechanism for operating said shifting device, consisting of a lever connected at one end to said shifting device, and arranged to connect with operating means at its other end, one of said ends being arranged to pass over a cam-shaped end of a spring-mounted block as it passes from one position to the other, and said block, whereby said spring operates to assist in throwing said lever and the shifting device, substantially as set forth.

14. In a carriage-operating mechanism, the combination, of the driving-gear, shifting device, and means for operating said shifting device which embodies dogs adjustably mounted on a carrying part by means of a worm-gear, said dogs being arranged to strike and operate the shifting device, substantially as set forth.

15. In a carriage-reversing mechanism, the combination of a dog-wheel, worm-hobbed on its periphery, dogs mounted on said wheel having worms to engage its periphery, which by raising are disengaged, allowing them to be slid to any position and are self-engaging and so held by a spring, said worm to make close adjustments with a lever connected to the carriage-reversing gearing, whereby said lever is operated, substantially as set forth.

In witness whereof I have hereunto set my hand and seal, at Waynesborough, Pennsylvania, this 22d day of August, A. D. 1899.
